UNITED STATES PATENT OFFICE.

JOHN W. FORCE, OF NEW BRITAIN, CONNECTICUT.

TURN-BUTTON.

1,087,084.

Specification of Letters Patent. Patented Feb. 10, 1914.

Application filed December 21, 1912. Serial No. 737,964.

To all whom it may concern:

Be it known that I, JOHN W. FORCE, a citizen of the United States, and a resident of New Britain, in the county of Hartford and State of Connecticut, have invented certain new and useful Improvements in Turn-Buttons, of which the following is a specification.

The object of this invention is to produce an article of the character described containing features of novelty and advantage.

The invention is illustrated in the drawings, in which—

Figure 1 is a side view with parts broken away to show construction. Fig. 2 is an end view of the base, showing the button in the other position from that shown in Fig. 1.

The particular purpose of this invention is to produce a button in which the movable member is locked as securely as possible in either position of adjustment and yet readily disengageable so that it may be turned from one position to another; and also to reduce the cost of manufacture to the greatest possible extent.

According to the drawings *a* denotes the base and *b* the turn button member held to the base by the pin *c* and provided with the usual spring *d*, which acts to draw the button down onto the base and yet permits of

its movement for disengagement of the locking means. These locking means comprise pins *2*, *2*, with their sides slightly tapered, adapted in one position to be received in the pockets *3*, *3*, in the top of the base, these pins being spaced apart so that they will lie snugly against the sides of the base when the button is turned to its other position, as clearly shown in Fig. 1. It will thus be seen that the button is effectively held in either position of adjustment, and that the construction is such as to require a minimum of operations in its manufacture.

I claim as my invention:—

In a device of the character described, a base having greater length than width, pockets in the top of the base near each end, a turn button rotatably mounted centrally of the base and having a limited longitudinal movement relatively thereto, and a pair of spaced pins located in the underside of said button and adapted in one position of the button to engage the sides of the base, and in another position of the button to engage said pockets.

JOHN W. FORCE.
